(57) **CLAIM**

The ornamental design for a key region for a keyboard, as shown and described.

DESCRIPTION

FIG. 1 is a perspective view of a key region for a keyboard showing my new design;

FIG. 2 is a top view thereof; and,

FIG. 3 is a top view showing the key region on a first exemplary keyboard.

The contrast in shading techniques on the upper surface of the keyboard designates a contrast in appearance, accomplished for example by color, material, and/or texture.

The broken line showing of the keys, the boundary of the claimed region, and the remainder of the exemplary keyboard in FIG. 3 is for illustrative purposes only and forms no part of the claimed design.
